TELEPHONE SYSTEM

Morris E. Griffins, Chicago, Ill., assignor, by
mesne assignments, to Associated Electric
Laboratories, Inc., Chicago, Ill., a Corporation
of Delaware

Application February 12, 1932. Serial No. 592,455

12 Claims. (Cl. 179—27)

This invention relates to telephone systems in general, and, particularly, to multi-office telephone systems; and its object is the provision of improved trunking arrangements whereby the traffic from different classes of lines may be effectively handled over the same switching apparatus and trunk groups.

General description

As is well known, it is desirable, when practical, to provide a single, large group of trunks or switches rather than several small groups due to the resultant increase in efficiency. In case traffic from lines with different service requirements is routed over such trunk or switch groups, there must necessarily be arrangements for distinguishing between the different classes of lines so that the particular service requirements of each line can be met. As an example, an automatic office in which both paystation lines and regular or flat-rate lines terminate may be provided with a single group of trunks extending to the toll switchboard. If there are a large number of lines in each class, separate switch trains may be provided for the various classes and connections may be extended to the toll trunks over different routes. This arrangement, however, is inefficient when the line groups involved are relatively small, and under these conditions it has been the usual practice to associate identifying means (usually tone apparatus) with the lines. An arrangement of this type is disclosed in the co-pending application of V. S. Tharp, Serial No. 512,047, filed January 29, 1931, on which Patent No. 1,868,956 was granted July 26, 1932, in which a tone source at a lineswitch is adapted to be connected through to a trunk by way of the release trunk or holding conductor. This arrangement involves the provision of special tone circuits for the lineswitch units, thereby adding to their cost, and, what is more objectionable, the tone applied to the release trunk conductor, which is included in the cable with the talking conductors, may induce disturbing currents in adjacent talking circuits unless special precautions are taken to prevent it. In the present invention, the objectionable features above mentioned are entirely eliminated by applying the tone to the toll trunks at the trunk repeaters. Further, provision is made for distinguishing between the lines of different classes without increasing the number of conductors in the local trunks extending from the selector banks to the trunk repeaters. This constitutes one of the features of the invention.

The foregoing discussion deals generally with

the problem of signalling ahead as to the character of a calling line. In addition, there is the problem of backward signalling when the lines involved have different requirements as to supervision. As a further example, the automatic office above discussed may serve as a tandem switching point for a manual office not directly connected with the toll switchboard. In this case also, a special switch train and separate route of access to the toll trunks could be provided for calls from the manual office, but this would be impractical if there were only a few manual office trunks. The present invention, therefore, contemplates the routing of calls from the manual office over the same switch train and trunk group that is used for calls originating in the automatic office, and provision is made for giving the kind of supervision required in each case. This arrangement constitutes another feature of the invention.

Description of drawings

The accompanying drawings comprising Figs. 1 and 2 show one embodiment of the invention. Fig. 1 shows switching apparatus located in an automatic office. Fig. 2 shows a toll trunk and associated equipment connecting the automatic office with a toll switchboard.

Referring to Fig. 1, there is shown a paystation line PS, a trunk line T, and a subscriber's line A, terminating, respectively, in lineswitches LS, LS1, and LS2. The lineswitches have access in common to a number of first selectors, such as selector S. The paystation line, which is of the postpay type, may be similar to that disclosed in the co-pending application of T. C. Riebe, Serial No. 344,689, filed March 6, 1929 on which Patent No. 1,844,684 was granted Feb. 9, 1932. Only the essential features of the coin-control apparatus have been shown in detail. Lineswitch LS has been shown for convenience as an ordinary rotary-type lineswitch, although any other suitable type of lineswitch or line finder may be used. The lineswitch is equipped with a discriminating wiper in addition to the usual line and test wipers, and a pair of terminals are provided for facilitating the connection of ground to the extra wiper in order to identify the class of line served by the lineswitch. Lineswitches LS1 and LS2 may be exactly the same as lineswitch LS, although in this particular instance it will be assumed that the discriminating terminals are not connected, and, consequently, these switches will have no ground connection to the discriminating wiper.

Selector S, also shown in Fig. 1, is a two-motion, Strowger-type selector. This switch is generally similar to the usual selectors except that additional contacts and a set of shaft springs have been provided for purposes to be described later. This selector, with other similar selectors, has access over certain levels of its bank to trunks extending to the next rank of local switches, and on a different level of its banks 5 access is had to trunks extending to the toll switchboard. The shaft springs, above mentioned, are adjusted to operate when the shaft and wipers are raised to the level in which the trunks to the switchboard terminate.

15 Referring now to Fig. 2, there is shown a trunk line T1 extending from the automatic office in which the apparatus of Fig. 1 is located to a toll switchboard located in a distant office. Repeater R is a trunk repeater of the same general type as 20 that disclosed in the Tharp application previously referred to. A differential relay connected in series with the line relay controls the various discriminating functions, such as class 25 signalling and supervision. The repeater is provided with the usual means for automatically removing tone from the trunk after the operator answers the call. Supervision is given by current reversal in connections where it is required. The 30 trunk line is arranged for two-way service, and, accordingly, an incoming selector is provided in connection with the repeater R. The trunks terminate at the switchboard in the usual line relay group L with which cord circuits of any 35 suitable type may be used for answering and extending calls. One such cord circuit C has been shown in part for convenience of description.

Detailed description

40 Having briefly described the invention and certain of its more prominent features, the operations involved in setting up connections in a system embodying the same will now be described in detail. A connection from paystation line PS to the toll switchboard will be considered first. 45 When the receiver is lifted at the station to initiate a call, a circuit for line relay 14 of the lineswitch may be traced from battery, winding of the relay, contacts 16, line conductor 1, right-hand winding of polarized relay 3, branch conductor 4, switchhook spring contacts 39, impulse contacts 6 of the calling device CD, transmitter, primary winding of induction coil 5, line conductor 2, and contacts 22, to ground. Relay 14 50 operates and closes the usual testing and busying circuits at contacts 23 and 24. The connection of ground to conductor 30 marks the calling line busy in the banks of the connectors. The lineswitch now proceeds to test the trunk on which its wipers are standing, and, if this is busy, steps 55 ahead in the usual way in search of an idle trunk. When an idle trunk is found, for example the trunk terminating on selector S, relay 13 operates, opens the circuit of relay 14 at contacts 16 and 22, switches the test wiper over from testing 60 to holding position by opening contacts 18 and closing contacts 19, connects ground by way of contacts 20 to discriminating wiper 28, and at contacts 17 and 21 connects line conductors 1 and 70 2 by way of wipers 26 and 29 and branch conductors 31 and 34 to conductors 35 and 38 of the trunk. Relay 14 is slow to release and maintains relay 13 operated until ground is returned on the release-trunk conductor from the selector. In the 75 selector, relay 52, which is bridged across the

trunk conductors by way of contacts 65 and 72, operates over the calling subscriber's loop and completes a circuit for relay 53 at contacts 73. Relay 53 operates, prepares the impulsive circuit at contacts 75, and applies ground to release-trunk conductor 36 at contacts 50.

It will be noted that a winding of polarized magnet 3 is included in the operating circuit of the line relay of the selectors. The magnet does not operate at this time due to the direction of current flow in its winding. The calling subscriber now dials the digit designating the operator's position, for example the digit 0, and the circuit of relay 52 is interrupted accordingly at impulse contacts 6 of the calling device. Relay 52 responds by deenergizing and reenergizing, and transmits a like series of impulses by way of contacts 74 and 75, windings of relay 54 and vertical magnet 56, to battery. The magnet operates in response to each impulse and raises the shaft and wipers opposite the level in which the toll trunks are accessible. Relay 54 operates in series with the magnet, and, due to its slow-releasing characteristic, remains operated throughout the series of impulses. On the first vertical step of the wipers the circuit is closed from ground at contacts 50, contacts 78, off-normal contact 69, relay 55, to battery. Relay 55 completes a locking circuit for itself at contacts 81 and prepares a circuit for the rotary magnet at contacts 80. Shortly after the last impulse of the series, relay 54 restores, opens the original energizing circuit of relay 55 at contacts 78, and completes the previously-prepared circuit of the rotary magnet at contacts 77. Rotary magnet 57 accordingly energizes and steps the wipers of the switch in on the first set of contacts of the called level. If the trunk terminating in this set of bank contacts is busy, the test wiper will find a busy marking ground, which, by way of contacts 67, 79, and 60, will reoperate relay 55. Relay 55 incidentally restores upon the operation of the rotary magnet due to the opening of its circuit at interrupter contacts 79. The reoperation of relay 55 results in the reclosure of the circuit of the rotary magnet and the wipers advance another step. These operations are repeated until an idle trunk is found, which, for convenience, may be assumed to be the trunk comprising conductors 85-87, extending to repeater R. This trunk being idle, the test wiper of the selector finds no busy marking ground on the test contact, and relay 55 does not operate. Further, if there is no ground on the test wiper, relay 51 is no longer shunted and operates over a circuit including ground at contacts 50, cam spring contacts 59, winding of relay 51, interrupter contacts 79, off-normal contacts 60, winding of relay 55, to battery. Relay 55 does not operate due to the high resistance of relay 51. Relay 51 opens the circuit of relay 52 at contacts 65 and 72, extends the calling subscriber's loop through to the repeater at contacts 66 and 71, opens the original test circuit and prepares a holding circuit for itself by opening contacts 67 and closing contacts 68, removes ground from the impulse contacts of relay 52 at contacts 69, and at contacts 70 completes a circuit for momentarily connecting the discriminating conductor to the lower talking conductor of the trunk. Relay 52 releases and opens the circuit of relay 53 which will release after a short interval. It will be recalled that the shaft springs are adjusted to operate when the wipers of the switch are raised to the level in which the toll trunks are accessible. As this is the case in the present instance, con-

tacts 64 are closed, so when relay 51 operates and before relay 63 restores, there is a momentary application of ground to the lower talking conductor of the seized trunk. The circuit for effecting this connection includes ground at lineswitch LS, strap 21, contacts 20, wiper 28, branch conductor 33, trunk conductor 37, shaft spring contacts 64, and contacts 70 and 88. The purpose of this momentary application of ground will be-
10 come apparent when the operation of the repeater is considered.

Referring now to the repeater, the switching through of the selector as above described extends the calling subscriber's loop by way of conductors 85 and 87, contacts 110 and 115, contacts 120 and 125, upper and lower windings of differential relay 104, upper and lower windings of relay 105, to battery and ground. Relay 105 operates and completes a circuit for relay 102 at contacts 128. It will be recalled that in the connection under consideration the selector after switching through momentarily applies ground via the discriminating conductor to the lower side of the trunk. This ground connection shunts 25 the lower windings of relays 104 and 105, thereby permitting relay 104 to energize over its upper winding alone. Relay 104 completes a circuit for relay 103 at contacts 127. Relay 103 operates, connects the trunk conductors directly to relays 30 104 and 105, independent of the reversing contacts of relay 101 by opening contacts 120 and 125 and closing contacts 121 and 126. Relay 103 also completes a holding circuit for itself at contacts 122, removes the normal ground connection 35 from the lower winding of battery-feed relay 101 at contacts 124, and at contacts 123 connects the relay winding through to ground on which a tone is superimposed. As a further result of the operation of relay 102, parallel circuits are completed for relays 108 and 109, the circuit of the former relay extending over contacts 119 and 142 and that of the latter relay over contacts 119 and 144. Relay 109 operates, disconnects the outgoing trunk conductors from the incoming switch 40 at contacts 148 and 153, connects ground to the upper trunk conductor at contacts 149, completes a locking circuit for itself at contacts 150, applies ring-back tone to the lower talking conductor of the repeater at contacts 151, and at contacts 152 connects the generator to the lower outgoing 45 trunk conductor. Relay 108 energizes at this time, but its single spring is weighted at one end and the spring accordingly vibrates and prevents the closure of contacts 147 for a long enough 50 interval to operate relay 107. Ringing current is accordingly transmitted over the outgoing trunk over the circuit described extending from the conductor designated GEN, contacts 152 and 148, trunk conductor 153, contacts 165, upper 55 winding of relay 159, condenser and contacts 174, trunk conductor 157, and contacts 137 and 149 to ground. Relay 159 operates and completes a 60 circuit at contacts 161 for the visual busy signal V and line lamp L. Relay 159 also completes a locking circuit for its lower winding by way of contacts 162 and 166. During the interval in 65 which ringing current is transmitted over the trunk the spring of relay 108 is vibrating. After a certain definite interval, the vibration ceases and the springs come to rest with contacts 147 closed. Relay 107 accordingly energizes in parallel with relay 108 and locks to ground by way of contacts 143 and 119. Relay 107 disconnects the trunk conductors from the ringing circuit at 70 contacts 137 and 146, and at contacts 138 and

145 extends these conductors through to the talking condensers and battery-feed relay of the repeater. A circuit is prepared for relay 106 at contacts 139, the original energizing circuit of relay 108 is opened at contacts 142, a new circuit is prepared for this relay at contacts 141, and the original energizing circuit of relay 109 is opened at contacts 144. Relay 108 restores but relay 109 remains energized over a locking circuit including contacts 150, 114, and 119. The subscriber is now receiving ring-back-tone to indicate that the operator is being signalled, and lamp L glows to notify the operator of the incoming call.
80 The operator answers the call by inserting the plug P of a cord circuit C into jack J, thereby completing a circuit for relays 160 and 167 in series over the sleeves of the plug and jack. Relay 160 opens the circuit of lamp L at contacts 163, closes an additional circuit for the visual signal at contacts 164, disconnects the upper winding of relay 159 from the trunk at contacts 174 and 165, and opens the circuit of the lower winding of relay 159 at contacts 166. Relay 159 restores. Battery-feed relay 101 of the repeater now operates over a circuit which may be traced from battery, upper winding of the relay, contacts 132 and 145, trunk conductor 158, ring contacts of the jack and plug, supervisory relay 168 of the cord circuit, tip contacts of the plug and jack, trunk conductor 157, contacts 138 and 130, lower winding of relay 101, contacts 135 and 123, through the tone transformer, to ground. Relay 168 is a polarized relay and does not operate at this time due to the direction of current flow in its winding. The tone applied to the trunk through the lower winding of relay 101 will now be audible to the operator who will have connected her telephone set to the cord circuit. The tone will indicate the character of the calling line. The operation of relay 101 as described results in the completion of an additional circuit for relay 102 at contacts 112, the opening of the holding circuit of relay 109 at contacts 114, and the closure of a new circuit for relay 108 by way of contacts 119, 113, and 141. It may be pointed out at this time that relay 101 on operating also actuates reversing contacts 110, 111, 115, and 116, but without effect in this particular connection due to the previous operation of relay 103 which by-passed the reversing contacts. Relay 108 again energizes, and its weighted spring vibrates as before. After an interval, the spring comes to rest and a circuit is completed by way of contacts 147 and 139 for relay 106. Relay 106 is slow-to-operate, and after an interval energizes, short-circuits the two windings of differential relay 104 by closing contacts 133 and 134, removes the tone ground from the lower winding of relay 101 at contacts 135, and connects direct ground to this relay at contacts 136. Relay 108 accordingly will remain operated as long as relay 101 is energized and the tone will be cleared from the trunk. In case the operator wishes to recheck the line, the tone may be reapplied to the trunk by momentarily withdrawing the plug from the jack.
90

The operator may now converse with the calling party and further extend the call as required. As there is no reversal of battery over the trunk comprising conductors 85-87, polarized magnet 3 of the paystation equipment is not operated, and the talking circuit is not interrupted. Any necessary charges will be made under the supervision of the operator, that is, the calling sub-
95 100 105 110 115 120 125 130 135 140 145 150

scriber's coin will actuate an audible signal in the usual manner to inform the operator as to the amount deposited.

When the calling subscriber hangs up at the 5 termination of the call, the loop circuit over which relay 105 of the repeater has been energized is opened and the relay restores. Relay 105 opens one point in the circuit of relay 102 at contacts 128, but this relay is now held operated over a circuit including contacts 112. Relay 105 also reverses the connection of relay 101 to the outgoing trunk conductors by opening contacts 130 and 132 and closing contacts 129 and 131. The reversal of current flow over the 10 trunk line energizes the polarized relay 168 of the cord circuit, which completes a circuit for supervisory lamp L1 at contacts 173. The operator may now release the connection by withdrawing the plug of the cord from the jack. This 15 operation opens the circuit of relay 101, which restores, and opens the circuit of relay 102. Relay 102 restores, removes the ground from release trunk conductor 86 at contacts 118 and at contacts 119 opens the holding circuit of relays 106, 20 107, and 108. These relays restore and the repeater is ready to receive the next call. The removal of ground from release trunk conductor 86 permits selector S and lineswitch LS to restore 25 in the usual way.

30 The operation of the paystation line apparatus in calls to local subscribers in the automatic exchange is not particularly concerned with the present invention and will not be described in detail. It may be pointed out, however, that in connections of this type, the selector is operated to connect with the trunk on one of the local levels and the shaft springs are not operated. The discriminating conductor accordingly is not connected to the local trunk and the connection is 35 extended in the usual way. Upon the call being answered, the connector reverses battery to operate the polarized magnet of the paystation apparatus which disables the talking circuit at that station. The calling subscriber then deposits the 40 necessary coin and the talking circuit is completed as described in the previously-mentioned Riebe application.

50 The establishment of connection from the manual office over trunk T to the toll switchboard will now be described. Upon the extension of the call over trunk T, lineswitch LS1 operates in the same manner as described for lineswitch LS, and the trunk is extended to an idle first selector, for example the selector S. It will be recalled that 55 the discriminating wiper of this particular lineswitch is not grounded, which is the distinguishing characteristic of this line. The selector is operated to the level in which the trunks to repeaters such as R are accessible, and selects an idle trunk in the same manner as described for the previous connection. The operation of the shaft springs at this time is without effect as there is no ground on the discriminating conductor. The line relay of 60 the repeater operates as before but differential relay 104 does not operate in this connection since there is no ground connection to the lower trunk conductor. Relay 103 accordingly is not operated in connections of this kind, and the reversing contacts of relay 101 are effective to reverse the connection of relay 105 to the incoming trunk upon 65 the answering of the call. Further, no tone is applied to the lower winding of relay 101 and the absence of this tone informs the answering toll operator of the character of the calling line.

Ringing current is applied to the line as in the previous connections, and the talking circuit is completed upon the operation of relay 107. Relay 101 operates when the call is answered and by opening contacts 110 and 115 and closing contacts 111 and 116 the direction of current flow is reversed over the trunk T, thereby giving the operator at the manual office the usual supervision. Relays 108 and 106 are operated under control of relay 101, but have no utility in the present connection aside from the fact that relay 106 short circuits the two windings of relay 104. This short-circuiting prevents the accidental operation of relay 104 during the connection, and also reduces the impedance in the talking circuit. The release of the connection is substantially the same as described for the previous connections.

Calls from flat rate stations in the automatic exchange such as from the station A are completed over lineswitch LS2, a selector S, and a repeater R, in the same manner as calls over the trunk T. The lineswitches for lines of this class are also characterized by the absence of ground on the discriminating wiper, and the repeater accordingly reverses battery when the call is answered. This battery reversal may be used for operating a meter or for other purposes which are well known.

100 Incoming calls from the toll switchboard to the automatic exchange may be extended over the trunk T1 by means of a dialling cord circuit (not shown), an incoming selector, and the local switches of the automatic office. The line relay of the incoming selector is bridged across conductors 154 and 156 and controls the operation of the selector in the usual way. The release relay 110 of the selector returns ground over release trunk conductor 155, which marks the trunk busy in the banks of the selectors, such as selector S, and thereby guards the trunk against intrusion during 115 incoming calls.

What is claimed is:

1. In a telephone system, a repeater, a trunk terminating in the repeater, means for extending calls from lines of a plurality of classes over said trunk and through said repeater, means for answering the calls, means in the repeater normally effective to reverse the direction of current flow over the trunk responsive to the answering of a call, and means in the repeater operated responsive to the extension of a call therethrough from a line of one of said classes for preventing the operation of said last means.

120 2. In a telephone system, a local trunk and an outgoing trunk connected by a repeater, means for extending calls from lines of a plurality of classes over said trunks and said repeater, means in the repeater normally effective to reverse the direction of current flow over said local trunk responsive to control over said outgoing trunk, and means in the repeater controlled over said local trunk and dependent on the class of the calling line for rendering said last means ineffective.

125 3. In a repeating device, a pair of incoming conductors, a relay bridged across said conductors, a second relay normally effective on operating to reverse the connection of the first relay to said conductors, a third relay controlled over said conductors, and means controlled by said third relay for preventing said second relay from effecting 130 the reversal of the first relay connections.

140 4. In a telephone system, a trunk terminating in a repeater, three relays, circuit connections including contacts of the first relay connecting the second relay to the trunk, other circuit connec- 145 150

5. In a telephone system, a repeater, a trunk comprising talking conductors, a test conductor and a discriminating conductor, means controlled over said talking conductors for setting the selector, contacts operated dependent on a particular setting of the selector, and means including said contacts for momentarily connecting said discriminating conductor to one of said talking conductors. 80
6. In a telephone system, a repeater, a trunk incoming to the repeater, a relay in the repeater bridged across the conductors of the trunk, a second relay in the repeater normally effective to reverse the connection of said first relay to the trunk conductors, means for seizing the trunk to extend calls of various classes through the repeater, means for momentarily unbalancing the trunk responsive to its seizure to extend a call of one particular class, and means in the repeater operated responsive to the unbalancing of the trunk for preventing said second relay from reversing the connection of said first relay to the trunk conductors. 85
7. In a telephone system, a local trunk and an outgoing trunk connected by the repeater, means for extending calls from lines of a plurality of classes over said trunks and said repeater, means for answering the calls, means in the repeater responsive to the answering of a call extended from certain of said lines for reversing the direction of current flow over the local trunk, and means responsive to the extension of calls from other of said lines for applying a distinctive tone to the outgoing trunk and for preventing the reversal of current flow over the local trunk upon such calls being answered. 90
8. In a telephone system, a local trunk and an outgoing trunk connected by a repeater, means for extending calls from lines of various classes over said trunks and said repeater, means for answering the calls, reversing means responsive to the answering of calls extended from certain of said lines for reversing the direction of current flow over the local trunk, means responsive to the extension of calls from other of said lines for connecting a tone source to the trunk line, and means responsive to the answering of calls from said other lines for disconnecting said tone source from the outgoing trunk and for operating said reversing means without reversing the direction of current flow over the local trunk. 100
9. In a telephone system, an automatic switch, means for directly operating the switch to select a group of outlets, means for automatically operating the switch to select an idle outlet in the group, and means dependent on the extent of the directive operation of the switch for momentarily placing a distinctive electrical condition on the selected outlet. 105
10. In a telephone system, an automatic switch, means for extending calls from lines of two classes to said switch, means for directly operating the switch to select a group of outlets, automatic means for further operating the switch to select an idle outlet in said group, and means dependent jointly on the class of the calling line and on the extent of the directive operation of the switch for momentarily placing a distinctive electrical condition on the selected outlet. 110
11. In a telephone system, an automatic switch, a trunk comprising two talking conductors, a test conductor and an auxiliary conductor terminating in said switch, outlets each comprising two talking conductors and a test conductor accessible to said switch, means for extending a connection over said trunk to said switch, means for directly setting the switch in selective relation to a group of outlets, means for operating the switch to select an idle outlet in said group, and means dependent on the particular setting of the switch for momentarily connecting the auxiliary conductor of said trunk to a talking conductor of the selected outlet. 115
12. A telephone system as claimed in claim 11 in which connections from lines of two classes are extended to the switch over the trunk and in which the class to which a line belongs is indicated by the presence or absence of a potential on the auxiliary conductor of the trunk. 120
55. In a selector switch, an incoming trunk 130
60. Means for connecting a line to a selector switch 135
65. Means for connecting a line to a selector switch 140
70. Means for connecting a line to a selector switch 145
75. Means for connecting a line to a selector switch 150

MORRIS E. GRIFFINS.
